US00D995957S

(12) **United States Design Patent** (10) **Patent No.:** **US D995,957 S**
(45) **Date of Patent:** **** Aug. 15, 2023**

(54) **PORTABLE PET RAMP**

(71) Applicant: **Xiaoting Zheng**, Shaoguan (CN)

(72) Inventor: **Xiaoting Zheng**, Shaoguan (CN)

(**) Term: **15 Years**

(21) Appl. No.: **29/882,214**

(22) Filed: **Jan. 12, 2023**

(51) LOC (14) Cl. **30-03**

(52) U.S. Cl.

USPC **D30/199**

CLAIM

The ornamental design for a portable pet ramp, as shown and described.

DESCRIPTION

FIG. 1 is a front perspective view of a portable pet ramp, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a partial enlargement of FIG. 1.

The broken lines in the drawings illustrate the portions of the portable pet ramp, which form no part of the claimed design.

1 Claim, 9 Drawing Sheets
